UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

MACHINE FOR APPLYING A COVER OR BINDING TO A CASING SECTION.

1,420,827.

Specification of Letters Patent. Patented June 27, 1922.

Application filed May 5, 1921. Serial No. 467,079.

To all whom it may concern:

Be it known that I, CHARLES FISHER, a citizen of the United States, residing at Chicago, in the county of Cook and State of

5 Illinois, have invented a new and useful Improvement in Machines for Applying a Cover or Binding to a Casing Section, of which the following is a specification.

The present invention relates particularly 10 to a machine for applying a cover or binding to a casing-section which is adapted to form a part of a book-form safe.

It may be stated preliminarily that a savings bank of the character here referred to 15 is known as a library-safe, and comprises a casing-section which corresponds with one side, the back, and the edges of a book, and a closure which corresponds with the other side of a book.

20 The present machine is adapted to preliminarily form the cover about a sheet-metal member which is adapted to form one side and the back of the casing of the safe and to removably secure the sheet-metal member and the partially folded cover to a 25 removable die or holder.

This work is preliminary to further operations in another machine, into which the die or holder, the attached sheet-metal member 30 of the casing, and the cover may be introduced. The primary object of the present invention is to provide simple and easily operated mechanism for performing the preliminary operation referred to.

35 The invention is illustrated, in its preferred embodiment, in the accompanying drawings, in which—

Fig. 1 represents a side elevational view 40 of a press embodying the invention, the die or holder being removed, and the handle of the actuating lever of the plunger being broken away; Fig. 2, a plan view of the machine; the dotted lines indicating the position of the cover mentioned; Fig. 3, a 45 broken perspective view, showing the die or holder in position in the bed of the machine and showing a cover for a book-form safe properly positioned on the bed and extending across the die; Fig. 4, a broken perspective view illustrating the preliminary folding 50 of the cover about the casing-section, the plunger being in the position which it occupies while forcing the casing-section into the die and thus folding the cover about that

55 portion of the casing-section which corresponds with the back of the book-form safe;

Fig. 5, a broken perspective view illustrating the manner in which the back of the casing-section and the folded cover are secured to the die; Fig. 6, a perspective view of the 60 holder or die employed; Fig. 7, a longitudinal sectional view of the die, the dotted lines indicating the position of the casing-section; and Fig. 8, a transverse vertical section showing the plunger forcing the casing-section 65 into the die and effecting the folding of the cover about the back portion of the casing-section.

In the construction illustrated, A represents the bed of a press which is provided 70 with a transverse slot or socket A' for receiving a die, the bed of the press being further provided on its upper side with transverse ledges or gage members A² and A³ and being also provided with lateral 75 gage members A⁴, these gage members being adapted to position a flexible cover, which may be of leather or artificial leather, upon the bed-plate; B, a standard which rises from the rear portion of the bed and has a 80 forwardly curved arm equipped with a guide B' for the plunger; C, a plunger working in said guide, said plunger being provided at its lower end with a transverse head or bar C'; and D, a lever mounted on the standard B and serving to actuate the plunger.

Removably mounted in the transverse slot or socket A' of the bed of the press is a die or holder A⁵. This holder is shown in perspective in Fig. 6. It is adapted to be transferred to another press and to be mounted in different positions in such press to enable the binding operations to be completed. However, in the present press, the holder A⁵ is entered only in the position shown in Fig. 95 3, that is, in such position that its concave side will be turned upwardly and in position to receive the rounded back of the casing-section.

The casing-section which is operated upon 100 in the present machine is shown in perspective in Fig. 4 and in cross-section in Fig. 8. It comprises a sheet-metal member E which forms one side 1 and the back 1^a of the safe-casing. The side-plate 1 is provided near 105 its edges with inwardly-struck clenching lugs 1^b which are for the purpose of securing to the inner margin of the plate an U-form edge member which is of angle-form cross-section, this edge member (not shown) 110 corresponding with the edges of the leaves of a book. In completing the structure of

the device, the U-shape member of angle-form cross-section has one flange turned inwardly and provided with perforations which receive the clenching lugs 1^b.
5 The cover for the casing, which may be of leather, artificial leather, or other suitable fabric, is designated 2. It has its corners cut away and provided with corner-tabs 2^a, as shown in Fig. 3. The marginal portions of 10 the cover are provided with perforations or recesses 2^b which are adapted to receive or engage the brads or clenching lugs 1^b of the casing-section, after such margins have been folded over the edges of the sheet-metal 15 member.

The die or holder A⁵ comprises a metal bar 3 which has its upper side provided with a longitudinal concavity 3^a which is adapted to receive the rounded back 1^a of the casing-section; and a pair of clamping-slides 4 movable in longitudinal guides 5 with which the bar is equipped at its ends. The clamping-slides 4 have their inner ends made concavo-convex in cross-section, thus providing 25 comparativey sharp curved edges 5^a which are adapted to fold the central portions of the projecting margins of the cover designated 2^c (see Fig. 4) inwardly over the inner surfaces of the end portions of the 30 curved back 1^a, it being understood that the material is first preliminarily tucked in by the operator, and that the slides 4 are then shoved inwardly to complete the folding operation and clamp the casing-section and the 35 cover to the die or holder A⁵, as shown in Fig. 5. The slides 4 are equipped near their inner ends with studs 4^a for limiting the outward movement of the slides and are equipped at their outer ends with thumb 40 pieces 4^b by means of which the slides may be actuated. It will be noted from Fig. 7 that the bottom of the recess 3^a is slightly below the plane of the bottoms of the slides 5^a, so that the slides can move over the metal 45 of the casing-back and the infolded tucks 2^c.

The bar 3 is equipped at one side near its ends with blocks 3^b which are adapted to engage the lateral edges of the bed-plate A when the holder or die is in position, as 50 shown in Fig. 3. These blocks are shown equipped with studs 3^c, which serve a function, when the holder A⁵ is employed in the other machine referred to, but which possesses no function in the present machine. 55 The bed-plate A' is equipped at its lateral edges with studs 6, the function of which is to prevent the die or holder A⁵ from being entered improperly in the socket A'.

The operative-portion or transversely elongated head C' of the plunger is provided at 60 its front side with vertical slots 7 which are so positioned as to accommodate the clenching lugs 1^b when the plunger moves downwardly, so as to engage the inner surface of the back portion 1^a of the casing-

section. The lower edge of the head C' is rounded, as indicated at 8, to conform to the curvature of the back 1^a.

The operating lever D is supported on the standard B by means of a link 9; and a 70 spring 10 serves to hold the plunger normally elevated.

In the operation of the device, the operator after placing the cover 2 in position on the bed-plate, places the casing-section E 75 in such position that its back-portion 1^a can be forced into the recess 3^a of the die or holder A⁵, while the plate 1 occupies a standing position in front of the plunger. The cover-section may be centered by causing the 80 lugs 1^b to register with the slots 7 of the plunger. The operator then depresses the plunger and thus forces the back-portion of the casing-section into the groove 3^a of the die, thus folding the cover about the back 85 1^a. While the plunger is held in depressed position, the operator folds the tucks 2^c inwardly over the inner surfaces of the back-portion 1^a and moves the slides 4 inwardly, thus clamping the back-portion of the casing- 90 section and the intermediate portion of the cover to the die or holder. The plunger is then retracted and the holder is taken from the press and transferred to another machine 95 which is capable of performing further operations and completing the construction of the safe.

The other machine referred to forms the subject-matter of my copending application No. 467,703, filed in the United States Patent Office of even date herewith.

From the description given, it will be understood that the present invention embodies means for expeditiously forming a cover about the back portion of a casing-section and clamping the casing-section and cover to a holder or die which is capable of being used in another press for completing the construction of the safe.

The foregoing detailed description has 110 been given for clearness of understanding only and no unnecessary limitations should be understood therefrom, but the appended claims should be construed as broadly as permissible in view of the prior art.

What I regard as new, and desire to secure by Letters Patent, is—

1. The combination of a bed provided with a socket, a holder in said socket adapted to accommodate the back-portion of a casing-section, a plunger adapted to engage and depress the casing-section and stretch the intermediate portion of a cover over the back-portion of said casing-section, and means for clamping the casing-section and cover to said holder.

2. The combination of a bed provided with cover-positioning means and provided also with an elongated socket, an elongated holder in said socket adapted to accommodate the

- back-portion of a casing-section, a plunger having an elongated head portion adapted to engage the back-portion of said casing-section and depress the casing-section and 5 stretch the intermediate portion of a cover over the back-portion of said casing-section, and means for clamping the casing-section and cover to said holder.
3. The combination of a bed provided with 10 a transverse slot affording a socket, an elongated die in said socket, clamping means mounted on said die, means for positioning a cover on said bed, and a plunger adapted to engage and depress a casing-section and 15 force the back-portion of said casing-section into said die, thus folding the intermediate portion of said cover about the back-portion of said casing-section.
4. The combination of a bed provided with 20 a socket, a combined die and holder comprising a bar fitting in said socket and provided with a concave upper surface, clamping members mounted on the ends of said bar, means for positioning a cover on said bed, 25 and a plunger adapted to engage the back-portion of a casing-section and force the casing-section and intermediate portion of the cover into said die, said clamping members being adapted to slide over the ends of the
- back-portion of said casing-section and clamp 30 the intermediate tucks of the cover to said back and clamp said back to said die.
5. In a machine of the character set forth, the combination of a bed provided with a socket, an elongated die and holder mounted 35 in said socket, slides movably mounted on the ends of said holder and provided with curved edges adapted to ride over the ends of the back-portion of a casing-section, means for positioning the cover on said bed, 40 and a plunger adapted to depress the casing-section against said cover and force the intermediate portion of the cover into said holder.
6. In a machine of the character set forth, 45 the combination of a bed provided with cover-positioning means and provided with a socket, an elongated die and holder removably fitted in said socket, clamping means mounted on said holder, and a plunger having an elongated head adapted to engage the back-portion of a casing-section and force the same into the die, said plunger being provided with vertical slots for accommodating the clenching lugs with which the 50 casing-section is provided.

CHARLES FISHER.
